CLAIM

The ornamental design for instrument panel display screens and a steering wheel assembly, as shown and described.

DESCRIPTION

FIG. 1 is a front perspective view showing instrument panel display screens and a steering wheel assembly of my new design;

FIG. 2 is a front view thereof;

FIG. 3 is a side view thereof;

FIG. 4 is a side view thereof, opposite that of FIG. 3;

FIG. 5 is a top view thereof;

FIG. 6 is a bottom view thereof; and,

FIG. 7 is a rear view thereof.

The broken lines (for example, the dashboard, the steering wheel airbag cover, the backside mounting structure for the display screens and steering wheel, and the center display screen control buttons) form no part of the claimed design.
